CLAIM

The ornamental design for a threaded bolt tool, as shown and described.

DESCRIPTION

This application relates to and claims priority to U.S. Design patent D628,866 issued Dec. 14, 2010 and U.S. Design application Ser. No. 29/378,664 filed Nov. 8, 2010 currently allowed, the entire contents of each of which are incorporated herein fully by reference.

FIG. 1 is a front perspective view of an end of a threaded bolt tool embodiment of the present invention, the claimed portion existing as shown.

FIG. 2 is a front elevation view of FIG. 1.

FIG. 3 is a right side elevation view of FIG. 1, the left side being a mirror image thereof.

FIG. 4 is a bottom plan view of FIG. 1, the top plan view being a respective mirror image thereof.

FIG. 5 is a front perspective view of an end of a threaded bolt tool embodiment of the present invention, the claimed portion existing as shown.

FIG. 6 is a front elevation view of FIG. 5, the rear view not being visible as disclaimed subject matter and thus not provided; and,

FIG. 7 is a bottom plan view of FIG. 5, the top plan view being a mirror image thereof.

The dashed lines shown in FIGS. 1-7 illustrate portions which form no part of the claimed design. There is no claim in FIGS. 1-7 to the portion of the tool following the break-identifier, as indicated by the use of a dashed-break line. Should this termination line need to be shown in different shadowed boundary line to reach this statement, adjustment will be made upon instruction from the office.
